ELECTRIC HEATER

Filed Aug. 31, 1927

UNITED STATES PATENT OFFICE.

MARTIN K. PURDY, OF STROUDSBURG, AND WILLIAM H. REAGLE, OF TOBYHANNA,
PENNSYLVANIA.

ELECTRIC HEATER.

Application filed August 31, 1927. Serial No. 216,638.

This invention relates to electric heaters and has for an object to provide a heater which may be made in a great variety of sizes for a great variety of purposes from 5 heating a building to heating a smaller body of water, the heating medium employed being water.

A further object of the invention is to provide an electric heater having chambers 10 for containing the electric heating elements with adjacent chambers through which the water circulates in the usual manner of circulating systems.

A further object of the invention is to 15 provide improved means for securing ready access to the interior of the device for replacing heating elements or other repairs or replacements as occasion may require.

With these and other objects in view, the 20 invention comprises certain novel features, elements, units, constructions, interactions and functions as disclosed in the drawings together with mechanical and functional equivalents thereof as will be hereinafter 25 more fully described and claimed.

In the drawings:

Figure 1 is a view in side elevation of the heating unit with parts broken away to show the interior construction.

30 Figure 2 is a transverse vertical sectional view taken on line 2—2 of Figure 1.

Figure 3 is a diagrammatic view showing a means for controlling the heat generated by the unit.

35 Like characters of reference indicate corresponding parts throughout the several views.

The improved heating element which forms the subject matter of this application 40 comprises a housing 10 of such size, shape and dimensions as adapted to perform the functions and produce the heat required. The housing 10 is provided with interior chambers 11 and 12 which will be referred 45 to as the heating chambers with narrow or thin chambers 13, 14 and 15 adjacent the heating chambers and to be referred to as the circulating chambers.

Upon the exterior of the housing 10 a 50 plurality of lugs 16 are provided so spaced and positioned that the heating elements 17 may be inserted through the heating chambers and attached to said lugs 16 in any approved manner as by the screws or bolts 18.

55 The heating units 17 are of a well known

commercial type and will not be further described except that they are provided with binding screws 19 to which are secured the incoming feed wires 20.

Upon the exterior of the housing and covering over the lugs 16 and the extended and secured ends of the heating elements 17 are cover members 21 which are secured in any approved manner as by forming lugs 22 thereon and bolting such lugs 23 formed upon the exterior of the housing 10. The cover members 21 are provided with relatively closed and insulated sleeves 24 to accommodate the passage of the several feed wires. The cover members 21 are also provided with means for observing the interior, consisting of a transparent sheet 25 of mica or other like heat-resisting material.

Upon the top and bottom of the housing 10, headers 26 and 27 are secured in any approved manner as by the use of the well known connecting means of flanges 28 and 29 with bolts 30. The headers 26 and 27 are provided with nipples 31 for the outflow, and 32 for the inflow, such headers communicating with the circulating chambers 13, 14 and 15 so that the cold water inflowing at the nipple 32 into the header 27 is heated in the circulating chambers passing upwardly into the header 26 and outwardly flowing through 35 the nipples 31.

At Figure 3 has been shown diagrammatically a switch box 33 for manually controlling the supply of electrical energy independently of each of the several heating elements. It is to be understood, however, that this is only shown as indicative of some type of control whereby the rapidity of heating may be varied and is intended to include not only a manual control but any automatic control responsive to the temperatures of the heated areas.

It is believed that the foregoing description of the construction with the explanatory matter relative to operation accompanying 100 the description will afford a complete understanding of the operation of the device and that further description of the operation would be superfluous.

What we claim to be new is:

1. An electric heater comprising a housing having heating chambers normally open to the atmosphere upon opposite sides, lugs formed upon the exterior of the housing adjacent the open sides, electrical heating ele- 110

- ments inserted through the heating chambers and secured to the lugs, cover members for the open ends of the heating chambers and for the extended ends of the lugs, means leading to conduits through the cover members into the heating chambers and connecting with the heating elements, and circulating chambers contiguous to and receiving heat from the heating chambers.
- 10 2. An electric heater comprising a housing having opposite sides normally open to the atmosphere, heating elements extended through the heating chambers and connected with the housing externally thereof, cover

members for the extended ends of the heating elements, means to accommodate conductors extended through the cover member into the heating chambers and connecting with the heating elements, transparent observation ports provided in the cover members, circulating chambers contiguous to and receiving heat from the heating chambers, and means to connect inflow and outflow instrumentalities with the circulating chambers.

In testimony whereof we affix our signatures.

MARTIN K. PURDY.

WILLIAM H. REAGLE.
